UNITED STATES PATENT OFFICE.

JOHN GEORGE LEYNER, OF DENVER, COLORADO.

FLUID-CONTROLLED DRILL-BIT SWAGING AND SHARPENING MACHINE.

No. 821,420.

Specification of Letters Patent. Patented May 11, 1909.

Application filed November 6, 1907. Serial No. 400,955.

To all whom it may concern:

Be it known that I, JOHN GEORGE LEYNER, a citizen of the United States of America, residing in the city and county of Denver and State of Colorado, have invented a new and useful Fluid-Controlled Drill-Bit Swaging and Sharpening Machine, of which the following is a specification.

My invention relates to fluid controlled 10 drill bit swaging and sharpening machines; and the objects of my invention are: first, to provide a fluid controlled drill sharpener provided with a group of squeezing and pressing dies adapted to act in unison and at 15 the same time to squeeze and press the ribs at the rock cutting head end of cruciform shaped drill tool steel, into proper form. Second, to provide a fluid controlled drill bit 20 sharpening machine, that is provided with drill steel gripping jaws, coöperating with a reciprocating dolly to form a plurality of V-shaped rock cutting lips on a drill bit, and with a group of swaging squeezer and presser dies 25 adapted to jointly engage at one operative movement all of the ribs and interstices of the rock cutting head portion of cruciform shaped drill tool steel, and squeeze and press it into perfect form. And third, to provide 30 a simple, quick action, powerful drill bit sharpening machine, which is adapted to receive a variety of gripping and forming dies, for sharpening drills of different styles. I attain these objects by the mechanism illustrated in the accompanying drawings, in 35 which:

Figure 1, is a front elevation of the improved drill sharpener. Fig. 2, is a rear elevation of the same. Fig. 3, is a central vertical, sectional view thereof, showing a drill 40 clamped in position to be acted upon by the squeezers. Fig. 4, is a side elevation of the drill holder and sharpener detached from its supporting standard. Fig. 5, is a view of a portion of the standard forming part of the 45 upper portion of the sharpener, the squeezers being removed. Figs. 6 and 7, are respectively a plan view and a side elevation of one of the pivoted squeezers. Figs. 8 and 9 are respectively a front and side elevation of a 50 piston-operated squeezer, which acts in conjunction with the pivoted squeezers.

Similar letters of reference refer to similar parts throughout the several views.

Referring to the drawings, the numeral 1, 55 designates the supporting stand of my fluid

controlled drill sharpener. This stand comprises a floor or foundation base 2, a hollow vertical column or standard 3, and a top or table portion 4, all of which are preferably of circular form. Upon this supporting stand, 60 I place the drill sharpener and holder, which comprises a cylinder 5, which sets on and is secured to the table portion of the stand by any suitable means, but preferably by bolts or cap screws 6. This cylinder is open at its 65 bottom, the table portion forming its lower cylinder head, and it is closed at its upper end by an integral head 7. This cylinder is provided with an axial bore or piston chamber, in which a piston 8 is reciprocally mounted, and which is provided with a short piston-rod or stem 9, that extends through an aperture 10, formed in the upper head of the cylinder.

A vertically projecting standard 11, is 75 formed on the top of the cylinder, having a central bore, which forms a continuation of the aperture 10, in the upper cylinder head 7. The thickness of this standard is less than the diameter of the piston stem, hence 80 its bore 12 is formed in diametrically opposite sides of the standard, while the piston rod projects laterally through the opposite faces of the standard as shown. The upper end of the piston rod, however, is reduced in 85 width to correspond to the thickness of the standard, and in this upper end is formed a recess, in which is secured a drill holding die 13. The bore 12 of the guide-way or standard 11, extends up into the standard a short 90 distance above the end of the piston stem, and at its upper end it terminates into a semi-circular curve, in which a die 14 is fitted, which is a counterpart of the die 13. The recess in the end of the piston rod, in 95 which the die 13 is secured, comprises two abutting semi-circular recesses of different diameters.

Upon the front side of the standard, which is the side from which the drill-bits are inserted in the jaw dies constituting the vise, I form a forwardly projecting ledge 34, to the under side of which I removably secure by bolts a swage die 35 which I term a clearance swage die. This die comprises a depending 100 V-shaped lip or die portion, which is adapted to work into the clearance spaces between the lips of a drill-bit, and which projects from a base portion, which is adapted to be removably secured by a set screw 36 to the 110

under side of the projecting ledge 34 of the standard. The ledge 34 terminates with downwardly extending ends, which project slightly beyond the sides of the standard 11, 5 and circular bearing recesses 37 are formed at diametrically opposite points on the front side of the standard, so as to coincide with semi-circular abutment recesses 38, on the inner edges of the depending ends of ledge 10 34. The surfaces of the recesses 38, merge into inwardly and downwardly inclined fans 39, which form supports, the object of which will presently appear.

Within the recesses 37, and the semi-circular abutment recesses 38, are pivotally supported a pair of squeezer jaws 40, by means of circular bosses 41, formed on the outer ends of the said jaws, which bear in the recesses 37. These bosses are of the same 20 diameter as the ends of the squeezers, and coincide with the said ends, so that while they rest in the recesses 37, the ends of the squeezers bear against the surfaces of the abutment recesses 38.

25 The inner ends of the squeezer jaws 40, terminate in V-shaped ends, the upper and under faces of which converge at an angle of 45 degrees, and in their inoperative positions the jaws rest upon the supporting faces 39, of 30 the depending ends of the ledge 34, as shown in dotted lines Fig. 17. The under sides of the jaws are formed with substantially V-shaped recesses 42, the purpose of which will presently appear.

35 The jaws 40 are held in their bearings by eccentric washers 43, which are secured by cap screws to the depending ends of the ledge 34, in such a manner that when in operative position they lie partially over the ends 40 of the jaws, and prevent them from becoming displaced, but which when the screws are loosened swing down and out of the path of the jaws, so that they may be withdrawn.

On the piston rod 9, below and in vertical 45 line with the die 35, is removably secured a block 43^a, the lower end of which rests upon a horizontal face formed on the piston, while the block is secured thereto by cap screws 44. This block is formed with a V-shaped 50 die 45, in line with the die 35, and on each side of the die 45 with upwardly extending lugs 46, terminating in semi-circular upper ends, which lie against the lower edges of the jaws 40, and which raise the said jaws, and 55 enter the V-shaped recess in their under edges as the piston approaches the limit of its upward movement, as will appear by reference to Fig. 1.

60 The arrangement of gripping and squeezing dies illustrated and described, is particularly adapted for finishing drill steels which are cruciform in cross section, but the arrangement of the standard 11, is such that when other styles of drills are to be sharpened, 65 the dies and squeezers illustrated may be

removed, and other dies and formers employed, these dies and formers being embodied in a separate application.

When a drill bit of cruciform tool steel is laid on the lower swaging die 45, with its ribs 70 straddling the V or wedge-shaped point, and the piston is raised, the lower die is carried up to the upper die, and the squeezer jaws are raised by the end lugs 46; and as the piston continues its upward movement, the 75 lugs pass into the recesses 42 of the jaws and at the same time the lower swage die raises the drill bit against the upper swage die, and the dies and jaws press into and smooth out the upper and lower sides of its ribs, as will 80 be more fully described hereinafter.

85 The cylinder is provided with a valve chest 47, which comprises a flange portion 48, formed on the side of the cylinder. The entrance to the valve chest is threaded, and a cover 54 is threaded to it, and is provided with a hexagonal wrench receiving portion by which the cover may be screwed into it. An axial aperture is formed through the cover, and a valve stem extends into and 90 through the cap and is coupled to the valve, and to its outer end a handle 56 is secured. This handle is threaded to the valve stem and its hub is split and is provided with a clamping bolt, by which after it is screwed onto the 95 valve stem it is rigidly clamped thereto by its clamping bolt. A hose connection 79 is connected to the valve chest, from which a hose which I do not show, can be connected to a supply of fluid pressure.

100 The rear end of the cylinder is provided with an integral vertical standard 80, which is provided with a circular aperture 81, in alignment with the axial center of the drill gripping dies when they are in the position 105 shown in Fig. 1. Within the aperture 81, I insert the hub portion of a hammer piston cylinder 82. The cylinder is formed with a circular flange 83, at one end, from which the hub projects, and the hub is inserted from the rear side of the standard, and the flange is bolted to the standard by bolts 84, which extend through and beyond the other side of the standard. I also secure to the opposite side of the standard, which is the front side, a dolly guide and support 85. This guide comprises a flange 86, which is bolted to the standard by the bolts 84, and a projecting head 87, provided with an axial bore 88, that is positioned in 110 alignment with the dies and the hammer piston cylinder, and a drill lip forming punch or dolly 89 is reciprocally mounted in the bore 79. This dolly comprises a shank portion 115 which is fitted snugly but reciprocally in the bore of the cylindrical hub, and a lip cutting head portion of greater diameter. The shank is made long enough to extend through the aperture in the support into the hammer cylinder and into the path of a hammer-pis- 120

125

ton 90, reciprocally mounted in the cylinder 82. The lipped end or head portion of the dolly is round, and the dollies are formed with heads of varying diameters to meet the requirements of the drills being sharpened. The cutting lips of the dolly are arranged either radially upon the face of its head, which is made at right angles to the axial center of the dolly, or a pair of these lips cross at right angles through the axis of the dolly head, in the case of a dolly which is used for cruciform drill steel. I preferably employ a full triangular or inverted V-shaped rock cutting lip on the dolly, and form the dolly for the character of drill desired.

The pneumatic hammer piston cylinder is provided with a removable rear cylinder head 91, which is preferably threaded to the cylinder and is provided with a wrench receiving nut. The hammer piston is made in two diameters and the cylinder's bore is consequently made in two diameters. The larger diameter of the hammer piston forms about one-third of the length of its smaller diameter portion, and a right angled shoulder 92 is formed at the junction of the larger and smaller portions of the piston. An axial aperture is formed in the rear end of the hammer piston, which extends into it from its rear end to near its front end, and a circumferential row of elongated port holes 93, is formed radially through the shell to intersect the inner terminal end of this axial aperture. I preferably use but four of these radial port holes and preferably place each pair of them at diametrically opposite centers to each other through the shell.

The cylinder is arranged to reciprocally support the piston, and an air inlet port 94 is formed in it, to which is connected one end of a pipe 95, which connects at its other end with the fluid supply port 70, of the valve chest 47, the pipe being connected to the nipple 75 by a union 96. The forwardly projecting hub portion 97 of the cylinder 82, is provided with an axial chamber 98, which is made a little larger than the diameter of the striking end of the hammer piston or the rear end of the shank of the dolly. The shank of the dolly extends into this chamber, and the striking end of the hammer piston also extends into it on the forward stroke of its reciprocal movement, and strikes the shank end of the dolly, as will be understood by reference to Fig. 3.

In Fig. 3, the hammer piston is in position to receive the actuating fluid to start it forward. The fluid enters through the port 94, and passes into the bore of the hammer piston, through the ports 93, and drives the piston forward against the dolly, and as the ports 93 pass within the chamber 98, the fluid exhausts into said chamber and out through an exhaust port 99. The fluid then

exerts a pressure upon the shoulder 92 of the hammer piston, and drives it rearward again.

The dolly is reciprocally mounted in its supporting head independently of the hammer piston, and is adapted to be struck by said piston on each forward stroke and driven against the opposing end of the drill bit. It is necessary, however, that the dolly be held normally away from the end of the drill bit, and in position to be struck by the hammer piston, and that after being struck and driven against a drill bit, it should be instantly returned independently of the rearward movement of the hammer piston, as it is essential that the rearward movement of the dolly be free and independent of the reciprocal movement of the hammer piston, and at the same time as positive and quick and have a resilient variable throw within the limits of its full reciprocal stroke, so that if the burying of its lip into the soft hot steel of a drill bit should make it slightly slower in its return stroke than the hammer piston, it would still make the greater portion of its return stroke before the hammer piston again struck it, but normally it should make its full return stroke slightly quicker than the hammer piston makes its backward stroke and be in position to receive the full force of the hammer piston's forward stroke.

The opposite side of the shank of the dolly is provided with oppositely arranged holes 100, which extend into it a short distance. Into these holes I extend the ends of a pair of springs 101, which ends are bent over at right angles to the body of the springs, and I extend the opposite ends of the springs into holes 102 formed into the top of the vise cylinder or base flange 5 of the standard 80. And I preferably secure the lower ends of the springs in these holes by forming threaded holes 103 in the sides of the cylinder, which extend into and intersect the holes 102, and into these threaded holes I secure set screws 104, which extend to and intersect the holes 102, and these set screws are screwed against the lower ends of the springs and securely held there within the holes 102. Coils 105 are formed intermediate of the ends of the springs and arranged under contractive tension, by which they exert pressure upon and hold the dolly normally against the end of its support and the inner end of its shank in the striking path of the hammer piston. The upper ends of the springs act to hold the dolly against rotative movement, as they are arranged to extend far enough into its opposite sides to remain firmly in place.

The peripheral surface of the lips of the dolly and the adjacent periphery of the head of the dolly, converge upon the same angle that is given to the conical entrance of the dies, so that should the hammer piston and the dolly be operated when a drill bit is not placed in jaws in striking relation to the

dolly or be operated when a drill bit is not in the jaws, the beveled peripheral surface of the head of the dolly will strike in the beveled tapering entrance to the die, which will receive the spent blows of the dolly without injuring the lips of the dolly.

Upon the forward portion of the cylinder 5, is formed a hub 110, having a threaded axial hole, in which one end of a bar or tube 10 111 is screwed. This bar extends forward parallel with the direction in which the drill bit extends, when clamped, and upon it is slidably mounted one end of a drill supporting arm 112, which is provided with a set 15 screw to secure the said arm at any desired point of the length of the bar.

The opposite end of the arm is provided with a rest 113, which is arranged and adapted to support the rear ends of the drill bits so 20 that they will rest in horizontal alinement with the center of the dies when gripped by said dies. —

The rock cutting drill bits to be resharpened or the drill steel in drill lengths upon 25 which it is desired to form rock cutting lips, are heated in a forge to a suitable degree of heat, and each drill bit or drill steel is inserted in the dies and gripped and held there by the pneumatic pressure of the upwardly 30 moving piston, and the rock cutting lips are formed on it by the reciprocating dolly, which is operated by the reciprocating piston 90, mounted in the cylinder 82. The drill gripping dies 13 and 14, have a circular 35 gripping surface, as shown and described.

The operation of my pneumatic drill sharpener is as follows: A supply of compressed air under the desired pressure is led from a source of supply through the pipe or 40 hose 79, a fragment of which is shown in Figs. 1 and 2. The handle 56, is then moved in the direction of the arrow—Fig. 4—when the actuating fluid will pass through the cylinder 5, below the piston 8, which will thereby be 45 raised to the position shown in Fig. 3. A drill bit or a bar of drill steel, the point of which is to be resharpened, or on which a new set of rock cutting lips is to be formed, is previously placed in the lower half die 13 of 50 the vise, so that its end to be sharpened is just about even with the front end of the die. The piston then moves up quickly and clamps the said drill bit against the upper half die 14 of the standard. In practice, I 55 preferably use a pressure of about 80 pounds per square inch, but less pressure will hold the drill bits satisfactorily. This pressure is so great that the half dies will make indentations into a cold bar of tool drill steel. The 60 piston hammer being in the position shown in Fig. 3, the actuating fluid, which is preferably air, on entering the cylinder passes into the bore of the piston hammer through the ports 93, and drives the hammer forward 65 against the dolly, which is thereby driven

against the hot end of the drill, upsetting it so that it spreads out against the surface of the bell-shaped entrance to the die, while at the same time the cutting lips are formed thereon. The very rapid reciprocating 70 movement of the hammer piston causes the dolly to strike with great rapidity against the drill bit, and the springs 101 draw the dolly back after it strikes each blow; thus the dolly automatically assumes its normal position after each blow independently of the air controlled reciprocating movement of the hammer piston.

In order to sharpen a drill, or form a new set of rock cutting lips on the end of the drill steel, the said steel is first heated to the required degree, and the heated end placed upon the lower die 13. The compressed air is then turned on, which causes the piston to rise, and the dies 13 and 14 to grip the drill 85 bar. The hammer piston and the dolly are actuated at the same time, and as the dolly strikes rapidly against the end of the drill bar it forms the cutting lips thereon, and at the same time upsets the hot end of the drill-bar 90 in the conical entrance to the gripping and holding dies, and thus re-forms the ribs and the tapering head portion at the cutting end of the drill. This first lip forming action of the dolly invariably leaves a somewhat uneven surface of metal in the bottoms of the V-shaped spaces between the rock cutting lips, and in addition, the ribs back of the lips are not as smoothly, regularly, and fully 95 formed by this first action of the dolly as is 100 required in a perfectly formed and sharpened drill-bit; consequently, it is necessary that the fins of metal at the bottoms of the recesses or spaces between the lips be pressed smoothly down, as these spaces form the 105 clearance passages for the rock cuttings from the cutting edges of the lips between and past the ribs of the head portion to the body of the drill bit, and also that the ribs be 110 smoothly pressed out along their sides between each other. These requirements lead to a second working, which consists in removing the drill-bar from the gripping and holding jaws. The operator then draws the drill bit out to the position shown in Fig. 3, when 115 it will rest in the V-shaped die 45, so that the edge of the die will extend into the space between the ribs (see Fig. 1), and consequently such edges or uneven welts or fins of metal as have been swaged up by the first working 120 action of the dolly bear directly on the edge of the lower die. The throttle valve is then opened by turning the crank far enough to open the port 69, leading to the vise operating cylinder, which causes the piston rod to 125 instantly rise, which raises the lower swaging presser die and the drill bit up against the upper swage presser die, which depends into the upper space of ribs on the upper side of the drill bar, and at the same time the lower 130

presser die raises the side swaging dies, which as they move upward move into the opposite side spaces of the upset head portion of the drill bit, and between the ribs of its newly-formed rock cutting lips. The upward squeezing pressure of the lower and upper presser dies and the lateral squeezing pressure of the side dies presses and squeezes the uneven surfaces of metal at the bottom of the 10 ribs, and also the adjacent sides of the ribs out smooth and even, and also shapes them up into the desired form, and presses the bottom apexes of the ribs into sharp clear straight lines down even with the longitudinal 15 plane of the body of the drill bar. The operator then instantly reverses the air pressure to the top of the piston, which instantly lowers the piston and the lower pressing die, and as the side presser dies are below the 20 horizontal plane of their pivotal centers, they instantly follow the lower presser die and piston down to the end of its and their downward operative movement, which releases the drill bit. The drill bit is then returned 25 to the gripping and upsetting jaws 13 and 14, with its diverging tapering ribbed head portion drawn back into the conical aperture of the dies, and with its already formed wedge-shaped rock-cutting lips positioned opposite 30 to the spaces between the lips of the dolly so that the dolly will fit into the lips already formed. The compressed air is then turned on to operate the vise jaws and to grip and hold the drill-bit. The piston hammer is 35 then started up and the dolly again strikes in the already formed lips, which completely shapes and smooths them up into perfectly smooth and clear-cut rock cutting lips.

While I have illustrated and described the 40 preferred construction and arrangement of my fluid controlled or pneumatic drill sharpener, I do not wish to be limited to the precise construction and arrangement shown and described, as many changes might be 45 made without departing from the spirit of my invention.

Some of the elements of this invention are shown in my pending applications, Serial Nos. 377,985 and 388,351.

Having described my invention, what I claim as new and desire to secure by Letters Patent, is:

1. In a drill sharpening machine, the combination with a cylinder, a standard on the 50 cylinder, a piston in the cylinder having a

stem projecting into the standard, of a die secured to the standard, a similar die secured to the piston stem in line with the first die, a pair of dies pivoted at their outer ends to the standard, their pivoted ends being on 60 a line at right angles to the piston stem, the inner ends of said dies extending toward each other, and being engaged by the piston stem on its upward movement, whereby said inner ends are raised and act in conjunction with 65 the dies secured to the standard and piston stem.

2. In a drill sharpening machine, the combination of a cylinder, a standard thereon provided with a projecting ledge, a piston in 70 the cylinder having a stem projecting into the standard, and means for operating said piston, with a pair of dies secured respectively to the piston stem and to the ledge of said standard; a pair of dies having circular 75 bearing lugs on their outer ends, which lie in corresponding recesses in the standard, one on each side of its vertical center, their inner ends extending toward each other, said pivoted dies being raised by the piston stem to 80 act in conjunction with the first pair of dies.

3. In a drill sharpening machine, the combination of the supporting frame, the cylinder, the yoke-shaped standard on said cylinder, and the piston reciprocally mounted 85 in said cylinder and standard, with a pair of squeezing half dies secured to said standard and piston arranged to register opposite each other, said squeezing dies being provided with introverted V-shaped lips registering 90 opposite each other and adapted to enter the spaces and fit between the ribs of cross-rib drill tool steel, the squeezer die of said piston being provided with projecting fingers on its opposite side portions, a pair of swinging dies 95 pivotally mounted on said standard at one end and provided with V-shaped jaw faces at their opposite ends arranged to be moved to register opposite each other to enter the spaces of and fit between the diametrically 100 opposite ribs of cross rib drill tool steel from said first named squeezer dies, each of said swinging dies being arranged to rest on the fingers of said piston's squeezer die.

In testimony whereof I affix my signature 105 in presence of two witnesses.

JOHN GEORGE LEYNER.
